UNITED STATES PATENT OFFICE.

ABRAHAM SCOVRONEK, OF JERSEY CITY, NEW JERSEY.

COLLAR-BUTTON SUBSTITUTE FOR SHIRTS.

1,409,244.

Specification of Letters Patent. Patented Mar. 14, 1922.

Application filed November 3, 1920. Serial No. 421,473.

To all whom it may concern:

Be it known that I, ABRAHAM SCOVRONEK, a citizen of the United States of America, residing at Jersey City, in the county of 5 Hudson and State of New Jersey, have invented certain new and useful Improvements in Collar-Button Substitutes for Shirts, of which the following is a specification.

The primary object of the invention is the 10 provision of means for readily mounting a collar upon the neck band of a shirt and dispensing with the use of a collar button or stud at the back of the neck of the wearer.

A further object of the invention is the 15 provision of a collar and shirt band structure that is easy and inexpensive to manufacture and whereby the employment of any metal adjacent the back of the neck of the wearer is obviated and a comfortable detachable 20 connection between the collar and the band of the shirt is provided.

A still further object of the invention is the provision of a shirt band structure adapted for mounting a collar thereon without bringing any of the attaching means 25 in contact with the neck of the wearer and providing a comfortable neck band with the collar readily detachably mounted thereon.

With these general objects in view the 30 invention consists in the novel combination and arrangement of parts hereinafter more fully described in connection with the accompanying drawing, and in which like reference characters designate corresponding 35 parts throughout the several views.

In the drawing,

Figure 1 is a top plan view of a neck band of a shirt with a collar detachably connected thereto, parts being broken away and a 40 portion of the neck tie illustrated in position,

Figure 2 is a perspective view of a collar having the attaching member thereon, and

Figure 3 is a perspective view of the outside of a neck band portion of a shirt provided with my invention.

Referring more in detail to the drawing, a neck band 10 upon the shirt 11 is provided of substantially the usual form with a collar button 12 or similar securing means provided through the overlapping forward ends 50 of the band 10, although I prefer to add a protecting flap 13 upon the inner end of the

band for preventing the button 12 from contacting the neck of the wearer. Spaced transverse slots 15 in the back 14 of the band 55 10 are provided for the reception of the inturned free ends 16 of a tab or strip 17 secured substantially centrally at the back of the inner ply 18 of a collar such as 19.

The tab ends 16 are spaced apart a distance substantially equal to the spacing of the slots 15 so as to be readily inserted through the slots from a point outwardly of the band 14 as best illustrated in Fig. 1 of the drawing. A protecting strip 20 is secured within the rear portion of the band 14 inwardly of the slot 15 for overlying the ends 16 when the collar 18 is in position upon the shirt. The lower edge 21 of the band 14 is preferably unattached to the shirt 70 11 adjacent the slots 15 to permit the ready insertion of the fingers beneath the rear portion of the band 14 to assist the ends 16 in mounting the collar 18 upon the band 14, although the edge 21 may be stitched to the 75 shirt 10 throughout the length of the band 14 is desired.

The tab 17 is secured to the inner ply 18 of the collar preferably by stitching 22. The position of a neck tie 23 within the 80 collar 19 when positioned upon the neck band is shown in Fig. 1, and while the form of the invention herein set forth is believed to be the preferred embodiment thereof, it will nevertheless be understood that minor 85 changes may be made therein without departing from the spirit and scope of the invention.

What is claimed as new is:—

In combination with a shirt, a neck band 90 thereon having a rear portion free from the shirt at its lower edge with spaced transverse slots, a collar adapted for wearing with the shirt, a separate tab member centrally secured inwardly of the rear portion of the collar and comprising a substantially elongated strip of fabric stitched intermediate its ends to the collar, the extreme free ends of the tab being projected inwardly for movable positioning through the slots with the collar in varying position upon the shirt band.

In testimony whereof I affix my signature.

ABRAHAM SCOVRONEK.
